2,383,530

SHOE SEWING MACHINE

Louis L. Barner, Endicott, N. Y., assignor to
United Shoe Machinery Corporation, Flemington,
N. J., a corporation of New Jersey

Application March 23, 1944, Serial No. 527,761

6 Claims. (Cl. 112—39)

The present invention relates to improvements in back rests for inseam sewing machines such as are used for sewing uppers to the soles of turn shoes or the welts and uppers to the insoles of welt shoes, examples of this general class of machines being illustrated in United States Letters Patent to Morrill No. 2,041,945, granted May 26, 1936, and to Eppler No. 1,108,560, granted August 25, 1914.

A machine of the type described in the patents referred to is equipped with a curved hook needle, a welt guide, if a welt shoe is being operated upon, or a back gage, if a turn shoe is being operated upon. With either type of work the support of the work in the machine frequently is supplemented by the use of a bunter or back rest contacting the bulging upper of a shoe close to and below the point of operation of the needle. As the sewing operation progresses around the shoe, the shoe upper rubs against the forward end of the back rest in an irregular manner, the back rest moving in and out as the shoe is twisted and turned to present the shoe properly to the needle and frequently marking or otherwise damaging the surface of the upper as it rubs along the upper during progress of the operation.

In order to prevent the upper as it rubs along the surface of the back rest from being marked or otherwise damaged, attempts have been made heretofore to provide a rotating roll or other non-marking shoe engaging member on the back rest. Prior shoe engaging rolls for this purpose have been mounted to rotate on a substantially vertical axis so that their outer surfaces will move with the shoe as the shoe is fed from one stitch forming position to another. Thus, the frictional rubbing movement of the bulging shoe upper along the rotating back rest member has been substantially reduced. It has been found, however, that the movement of the bulging shoe upper, while presenting a shoe to the stitch forming devices of a machine such as disclosed in the above-noted patents, is of a non-linear nature, the surfaces of the upper moving vertically and swinging in many directions about the point of needle operation so that in spite of the use of a roll or other member rotating about a vertical axis on the back rest, the frictional rubbing engagement of the shoe upper with the rotating member is not sufficiently eliminated to avoid marking or otherwise damaging the upper of a shoe being operated upon, particularly with those shoes having light-colored or fancy-finished uppers. Furthermore, an upper contacting roll rotating on a vertical axis causes a unidirectional

effect, resisting vertical movement of the shoe without a similar horizontal resistance, and is not conducive to easy presentation of the shoe to the machine.

5 The object of the present invention is to improve generally the construction and mode of operation of a welt and turn shoe sewing machine so that the movements in any direction required to present a shoe to the stitch forming devices of the machine during sewing will meet with less resistance than heretofore, while at the same time substantially all possibility of marking or otherwise injuring the finished surface of the bulging shoe upper will be avoided, and, accordingly, the 10 herein illustrated embodiment of an important feature of the present invention resides in a curved hook needle inseam sewing machine having a bunter or back rest slide, at the forward work engaging end of which there is rotatably mounted a button having an axis of rotation substantially horizontal or substantially parallel to a tangent to that portion of the needle engaging the work during sewing. In the form illustrated, the rotatable button on the back rest acts on the 15 bulging upper surface of a shoe substantially below the needle at a location where the upper will engage the button above its axis of rotation while the toe portion of the shoe is being sewn and below that axis while the shank of the 20 shoe is being sewn. By so locating the rotary axis, the button will be caused to rotate during movement of the shoe in one direction while the toe is being sewn and in the opposite direction while the shank is being sewn, thus insuring rotation of the button without tendency to abrade, 25 mark or otherwise injure the upper at any time. Between the times the toe and the shank of the shoe are being operated upon, the upper covering the ball portion of a shoe contacts the back rest. 30 The upper in the ball portion of the shoe merges with the toe and shank portions and usually is characterized by rapidly changing curvatures. In order to present the shoe properly to the stitch forming devices, particularly along the ball portion, it is the practice for an operator to turn 35 the shoe somewhat in anticipation of the approach of these curvatures. Turning the shoe in this way causes the point of contact between the shoe upper and the button on the back rest, 40 according to this feature of the invention, naturally to be located somewhat ahead of the rotary axis of the button. In sewing along the ball portion of the shoe, the curvature of the shoe bottom requires also a swinging movement about a 45 horizontal axis passing through the sewing point,

resulting in a vertical movement of the upper along the point of contact with the back rest where the contact point is ahead of the sewing point.

With the upper contacting the button at a point ahead of the rotary axis of the button, vertical movement of the upper surface at the point of contact will cause the button to rotate rather than rub along the surface of the upper, as in the case of a fixed back rest or a roll rotating on a vertical axis. Also, it is along the ball portion of the shoe that the greatest vertical and swinging movements are required to present the shoe properly to the operating devices. While sewing along the ball portion, due to the increasing bulge of the upper beyond the edge of the shoe bottom, the point of contact between the button and the upper changes and moves from a position above the rotary axis of the button to a position below the rotary axis. As a result, the button changes its direction of rotation gradually. In addition, because of the vertical curvature of the shoe bottom, the forward linear movement of the upper along the point of contact with the back rest terminates temporarily, and the shoe is given an easy unresisted swinging movement about the point of sewing operations.

These and other features of the invention consist of certain constructions, arrangements and combinations of parts, the advantages of which will be clearly understood from the following description taken in connection with the accompanying drawing, in which

Fig. 1 is a view in right-hand side elevation of a portion of a shoe sewing machine embodying the present invention;

Fig. 2 is a detail view on an enlarged scale of some of the parts of the machine illustrated in Fig. 1, together with a shoe shown in section in operating position while sewing along the shank of the shoe;

Fig. 3 is a similar view, illustrating the positions of the parts while the toe of the shoe is being sewn;

Fig. 4 is a detail plan view, illustrating the positions of the back rest button in the machine with relation to a shoe while sewing at the ball line of the shoe; and

Fig. 5 is a detail view in elevation, indicating the point of contact of the surface of a shoe upper while sewing along the ball portion of the shoe.

The machine illustrated in the drawing is intended to sew a welt to a Goodyear type of shoe and is provided with the usual stitch forming devices including a curved hook needle 2, a looper 4, a thread finger 6, a channel guide 8, a welt guide 10, and a back rest or bunter slide 12 pressed yieldingly within a horizontal guideway 14 toward the front of the machine. During sewing operations the slide 12 is moved as the position of the shoe is changed and is intermittently locked and released by mechanism 13 similar to that disclosed in United States Letters Patent to Eppler No. 1,142,157, granted June 8, 1915, and in the patents above identified. Other operating parts of the illustrative machine also are similar to those disclosed in the patents except for the work engaging end of the back rest slide, as will be described more fully hereinafter.

The forward end of the back rest slide of the machine embodying the present invention is formed with an offset lug 16 having a vertical slot 17 into which is adjustably clamped a bushing 18. The bushing 18 rotatably receives a horizontal spindle 20 attached at its forward end to or

5 integral with a convex button 22 the exposed surface of which comprises a segment of a sphere. On the forward face of the lug 16 is a thrust bearing plate 24 against which is pressed a shoulder 26 beneath the button, acting to space the button 22 from the thrust plate 24.

For convenience in assembling the parts, the thrust plate 24 is formed integrally with the bushing 18 and the rearward end of the bushing threadedly receives a clamp nut 28 acting against a washer 30 to secure the thrust plate and bushing to the lug 16. For retaining the spindle 20 against lengthwise movement in the bushing, the rearward end of the spindle is threaded internally and a screw 32 entering the threaded portion of the spindle has a head projecting radially from the axis of the spindle sufficiently to overlap the internal diameter of the bushing.

The arrangement of the lug 16 and the bushing 18 is such as to hold the spindle on a horizontal rotary axis, indicated at 34, parallel to the movements of the slide 12 and vertically spaced within a plane 36 defined by the needle, said axis lying outside the needle and beneath and parallel to a line tangent to the nearest portion of the needle which engages the shoe. The upper of a shoe presented to the machine contacts the surface of the button at the intersection of a line 38 (Fig. 3) above the axis 34 of the spindle while sewing about the toe of the shoe. While sewing along the shank of the shoe (Fig. 2), the button will engage the upper at the intersection of a line 40 below the rotary axis of the button. Hence, in these two sewing positions of the shoe, the button will be rotated in opposite directions, as indicated by the two arrows in Figs. 2 and 3. Between these sewing positions, illustrated in Fig. 4, in order to present the shoe properly to the stitch forming devices, the greatest degree of angular or swinging movement is imparted by reason of the bottom curvature along the ball portion.

The swinging movement of the shoe about an approximately horizontal axis while sewing the ball portion in approaching the shank, as shown in Fig. 5, is of sufficient extent to cause the upper, along that area contacted by the back rest to terminate temporarily its forward linear movement and, particularly with high-arch shoes, to reverse its linear movement slightly. Reversal of the linear movement in that area of the upper, contacted by the back rest causes the button 22 also to reverse its direction of rotation. As the sewing continues along the ball portion of the shoe, the point of engagement between the upper and the button moves downwardly past the rotary axis of said button at that side of the button axis, with respect to the direction of feed, in advance of the button axis, as indicated by the arrow in Fig. 5. When the sewing along the ball portion of the shoe is nearly completed, the point of contact 42 of the upper with the button is at the intersection of the line 44 with the upper, in Figs. 4 and 5, below the rotary axis, with respect to the direction of feed, and, since the curvature of the shoe bottom is such as to require no further substantial swinging movement in presenting the toe of the shoe to the stitch forming devices, there will be but little change in the point of contact between the upper and the button. Eventually, when the shank of the shoe is reached, the point of contact 42 between the upper and the button will travel to a position more nearly directly below the button axis, in line with the sewing point. The rotation of the button is reversed, in the manner described, twice

during each sewing operation, once after starting, while leaving the shank, and again upon reentering the opposite side of the shank.

To prevent indentation of the upper while, at the same time, avoiding the possibility of contact between the relatively sharp edges of the button and the upper, the spherical upper engaging surface of the button 22 is made with a sufficiently large radius to engage a substantial area on the surface of the bulging shoe upper. By providing a substantial area of contact, not only is indentation avoided but also the pressure of the upper against any unit area of the button is kept below that which will cause appreciable marking of the upper or injurious effects from abrasion between the upper and the surface of the button, even when the button is composed of relatively soft metal. Furthermore, the upper engaging surface of the button is finished with a smooth polish so that rotation at the point of engagement with the upper has no substantial injurious effect.

The use of a button of this nature, located and arranged as indicated, avoids nearly all resistance to the positioning movements of the shoe while presenting it to the machine, such as occur when a stationary work engaging member is provided on the back rest slide. Also, with the button rotating about a horizontal axis, there is no substantial tendency for the shoe, while its position is being changed during sewing operations, to deviate from the desired direction of movements as a result of directional effects from rotation of a roll on a vertical axis, the surface of which acts to steer the shoe along a right line passing through the point of contact.

The nature and scope of invention having been indicated and a preferred embodiment having been specifically described, what is claimed is:

1. An inseam shoe sewing machine having stitch forming devices including a curved hook needle, and a back rest slide, in combination with a button rotatable on the slide about an axis substantially parallel to a line tangent to that portion of the needle engaging the work.

2. An inseam shoe sewing machine having stitch forming devices including a curved hook needle, and a back rest slide, in combination with a button rotatable on the slide about an axis substantially below and parallel to a line tangent to that portion of the needle engaging the work.

3. An inseam shoe sewing machine having stitch forming devices including a curved hook needle, and a back rest slide, in combination with a button rotatable on the slide about an axis substantially parallel to a line tangent to that portion of the needle engaging the work and spaced below the needle sufficiently to cause the face of the button to engage the bulging upper of a shoe being sewn above the axis of the button while sewing the toe portion of the shoe and below the axis of the button while sewing the shank of the shoe.

4. An inseam shoe sewing machine having stitch forming devices including a curved hook needle, and a back rest slide, in combination with a button rotatable on the slide about an axis substantially parallel to a line tangent to that portion of the needle engaging the work and in the plane of the needle outside the needle arc.

5. An inseam sewing machine having stitch forming devices including a curved hook needle, and a back rest slide, in combination with a button having a convex face rotatable on the slide about an axis substantially parallel to the movements of the slide during sewing operations.

6. An inseam shoe sewing machine having stitch forming devices including a curved hook needle, and a back rest slide, in combination with a work engaging button mounted for rotation on the back rest slide having for its work engaging surface a segment of a sphere so located and of sufficient area to enable the point of engagement of the shoe to move across the rotary axis of the button during sewing operations.
